UNITED STATES PATENT OFFICE.

OTTO EICK, OF BALTIMORE, MARYLAND.

BRUSH FOR CLEANING BOTTLES OR OTHER CONTAINERS.

1,106,034.

Specification of Letters Patent.

Patented Aug. 4, 1914.

Application filed June 10, 1907, Serial No. 378,228. Renewed June 3, 1914. Serial No. 842,792.

To all whom it may concern:

Be it known that I, Otto Eick, a citizen of the United States, residing at Baltimore city, State of Maryland, have invented certain new and useful Improvements in Brushes for Cleaning Bottles or other Containers, of which the following is a specification.

My present invention pertains to improvements in brushes for cleaning bottles or other containers, the construction and advantages of which are hereinafter set forth reference being had to the annexed drawings, in which:

Figure 1 is a sectional elevation of the brush; Fig. 2 a similar view, the brush being turned through an arc of ninety degrees from that shown in Fig. 1, and the lower portion being broken away; Fig. 3 a transverse sectional view taken on the line 3—3 of Fig. 1; Fig. 4 a perspective view of the preferred form of the cleaning or brush section carried at the outer end of the spindle; Fig. 5 a perspective view of the brush member which extends lengthwise of the spindle; and Fig. 6 a sectional elevation showing a modified form of the upper brush member.

The main object of the present invention is to provide a simple and efficient brush for cleaning bottles, the brush being especially adapted for use in what is known as a spindle cleaning machine.

A further object of the invention is to provide means whereby the bottom of the bottle and the corners formed at the junction of the bottom and the side walls of the bottle may be thoroughly cleaned, the side walls and neck of the bottle being likewise thoroughly cleansed.

With these and other objects in view a detailed description of the invention will now be given, reference being had to Figs. 1 to 6 inclusive:

In said figures A denotes a tube or hollow spindle provided with a spiral slot B extending longitudinally thereof, the slot terminating at its upper end in an enlargement or circular opening C, and at its lower end in a similar opening D. The lower opening may, however, be omitted if so desired.

The side brush members are formed as shown in detail in Fig. 5; that is to say, the fingers E, preferably ribbed, are connected at their inner ends or formed integrally with a trough-shaped or half round body

section F; both parts of the structure being formed of rubber cast and cured in one piece. To position the fingers and the member one end of the half round body member F is passed into the opening C or D, as the case may be, and forced downwardly into the tube, the fingers projecting outwardly through the slot B and arranging themselves in spiral formation about the tube as clearly indicated in Fig. 1.

By properly proportioning the length of the member F the openings C and D may be left free, or one or both of said openings may be closed as desired, the water which is forced through the tube passing out through said openings and also at the upper end of the tube. The upper end of the tube is preferably threaded externally, and a brush member of the form shown in Fig. 4 is mounted thereon. Said member comprises a body portion G from which extend outwardly at approximately right angles to each other two arms H and I. The arm H is slightly longer than the arm I, and is provided at its outer end with a flattened head J, the edge of which is sharpened or beveled so as to pass into the angle formed at the junction of the bottom and the side wall of the bottle as the brush is rotated. The member or arm H is also preferably formed with a wing or wiper K upon its upper face, and to one side of the center thereof. Said wing or wiper acts upon the bottom of the bottle, and working in conjunction with a similar wing L formed upon the arm I will thoroughly clean the bottom of the bottle. The outer end of the arm I is beveled as at M, so as to enter the angle formed at the junction of the bottom and the side walls of the bottles, said member coming into operation when small bottles are being cleaned.

Each of the arms H and I is provided on its under face with a strengthening rib N and O respectively. The arms normally stand outwardly in the position indicated in the drawing, and are not dependent upon the centrifugal action to throw them into working position with reference to the bottle.

As will be seen upon reference to the dotted lines, Fig. 4, the body portion G is provided with a socket adapted to receive the upper threaded end of the tube A. This socket is elongated or flattened and connects with the opening P standing in alinement

with the opening in the upper end of the tube when the brush member is positioned upon the tube. By having the socket flattened the brush will be more firmly held 5 upon the upper end of the tube after the same is forced thereover, the rubber of which the brush member is formed tending to contract and bind upon the tube.

It is conceivable, of course, that in so far 10 as the use of the side brush members in the form illustrated is concerned, they may be used independently of any other brushing member on the tube or spindle, and that they may also be used in conjunction with 15 other forms of brushing members upon the ends of the tube or hollow spindle. Thus, for instance, as shown in Fig. 6, a wabbling brush may be employed. In this case the upper end of the tube is interiorly 20 threaded, and a threaded stem Q extending downwardly from the hollow cap-piece R is screwed into the spindle, a cross-pin or rivet S passing through the side walls of the hollow cap-piece R. It also passes 25 through an eye or loop T formed by the wires U to which the bristles or wires V are secured.

By proportioning the parts as shown the brush will drop to one side of the center of 30 the cap-piece, and be thrown around in the bottle or other container as the spindle or tube is rotated.

As will be readily appreciated by those skilled in the art, the water or other cleaning 35 fluid which is flowing into the spindle will be ejected through the openings C and D, or one as the case may be according to the adjustment of the body portion F within the tube, and also through the opening 40 P in the upper end of the brush member, or through the threaded tubular portion Q if the modified form of the upper brushing member be employed. The upper brushing member in the preferred form will conform 45 to the shape of the bottom of the bottle and also to the side walls thereof to a greater or less extent, and the fingers E will thoroughly scour and rub the neck of the bottle and the side walls below the neck portion. 50 It has been found in practice that the brush as herein constructed thoroughly cleans the bottles and removes any deposits therefrom.

Having thus described my invention what I claim is:

55 1. The combination of a tube or hollow spindle provided with a spiral slot extending longitudinally thereof; a U-shaped body member mounted within the tube in the rear of the slot, and a series of fingers extending 60 outwardly from said body member through the slot.

2. In combination with a tube or hollow spindle provided with a slot extending longitudinally thereof; a body member substantially semi-circular in cross section arranged

in the tube adjacent to the slot, and a series of fingers extending outwardly from said body member through the slot.

3. The combination with a tube or hollow spindle provided with a spiral slot extending longitudinally thereof, the slot being provided with an enlarged opening at one end; a flexible body portion adapted to be passed through the enlarged opening into the tube and to occupy a position in the rear of the slot, and a series of fingers extending outwardly from the body portion through said slot.

4. In combination with a tube or hollow spindle provided with a spirally arranged slot extending longitudinally thereof, said slot being provided with an enlarged opening at one end; a body portion substantially semi-circular in cross section adapted to be passed through said enlarged opening and to occupy a position in the rear of the slot, and a series of fingers extending outwardly from said body portion and through the slot.

5. In combination with a tube or hollow spindle provided with a longitudinally disposed slot having an enlarged opening at each end thereof; a body portion adapted to be passed into the tube through one or the other of said openings and of a length somewhat less than the length of the slot and the openings, and a series of fingers extending outwardly from the body portion through the slot whereby upon shifting the body portion within the tube one or the other of said enlarged openings may be closed.

6. In combination with a body portion provided with a longitudinally disposed slot having enlarged openings at its ends, the body portion being substantially semi-circular in cross section, and a series of flexible ribbed fingers extending outwardly from said body portion through the slot.

7. In combination with a tube or hollow spindle, a series of fingers extending outwardly from the body portion, said fingers being radially disposed about said spindle, and a brushing member carried at the upper end of the spindle.

8. In combination with a tube or hollow spindle, a series of flexible fingers extending outwardly from said body portion, said fingers having a spiral relation with reference to the tube and the tube having an opening adjacent to the fingers for passing water therethrough, and a brushing member carried at the outer end of the spindle provision being made for the passage of water from the tube adjacent to said brushing member.

9. In combination with a tube or hollow spindle; a flexible brush member adapted to be secured directly to the outer end thereof, said member having an opening therein for the passage of a cleansing fluid therethrough

and likewise having a socket portion of a
normal cross-section in one direction less
than the cross-section of the spindle, where-
by when the brush member is secured in
5 place upon the tube its walls will hug the
tube and effect a tight joint therewith with-
out unduly stretching the walls.

In testimony whereof I have signed my
name to this specification in the presence of
two subscribing witnesses.

OTTO EICK.
